UNITED STATES PATENT OFFICE

JOSEPH EDWIN BURGESS, OF NEW YORK, N. Y., ASSIGNOR TO THE UNITED STATES PRINTING & LITHOGRAPH COMPANY, OF BROOKLYN, NEW YORK, A CORPORATION OF OHIO

DISPLAY TOY AEROPLANE

Application filed June 20, 1928. Serial No. 286,972.

My invention relates to toy aeroplanes, and has for its primary object to provide a toy aeroplane which can be economically made of a single sheet of paper or cardboard, for 5 convenient packing and transportation, and when assembled will form an attractive miniature of an aeroplane of the monoplane type which can be advantageously used for display or advertising purposes.

10 To this end my invention in its present embodiment consists primarily of a blank or sheet of roughly T-form, the tail portion of which is adapted to be folded upwardly along a longitudinal line, and which has rear- 15 wardly converging slits formed thereon in which the wing portion, when folded backward thereover, can be inserted to form the fixed transverse wing of the aeroplane.

Between the tail portion and wing portion 20 of the blank is a narrower fuselage portion from opposite sides of which project laterally bracket portions formed with rearwardly extending leg portions, the bracket portions being formed with end tongues 25 which, when the tail portion is folded to form the chassis, are inserted in slits to fix the legs in position, with the tail, to support the aeroplane in its rest position.

In order that my invention in its entirety 30 may be fully understood I shall first describe in detail the mode in which I at present prefer to carry the invention into practice, and then particularly point out the invention in the claims.

35 Reference is to be had to the accompanying drawings forming part of this application in which like parts are designated by the same numbers in all the figures.

Figure 1 is a plan view of the blank from 40 which the toy aeroplane embodying my invention is formed.

Figures 2, 3, and 4 are side, end and plan views respectively of the said toy aeroplane.

The blank shown in Figure 1 is formed 45 preferably of a single sheet of paper or cardboard cut in roughly T-form with a transverse wing portion 5, a tail portion 7, and a narrower fuselage portion 6, joining the wing and tail portions.

50 The tail portion 7 is adapted to be folded

upwardly along a central longitudinal line 8 extending from the tail end 9 to a point 10 behind the fuselage portion, and on the outside of two nearly longitudinal lines 11 diverging from the point 10 to points 12 55 spaced laterally on the fuselage portion to form and stiffen the fuselage of the aeroplane.

On the rear end of the tail portion 7 are formed lateral extensions 12, which when the 60 tail portion is folded upward into V-section as shown form the rudders of the aeroplane.

The tapering portion 13 between the diverging lines 11 forms the flat bottom of the fuselage when the same is formed as de- 65 scribed.

In the sides of the fuselage portion about opposite the point 10, are cut inwardly and rearwardly converging slits 14, and forward thereof the opposite edges of the fuselage 70 portion are cut to form forwardly and inwardly converging curves 15, succeeded by forwardly and inwardly converging straight lines 16, from the forward ends 17 of which the edges of the fuselage portion extend inward on a slight incline to the points 12 previously mentioned.

In the middle of the forward edge of the wing portion 5, is cut a rearwardly extending slit 18. 75

From opposite sides of the fuselage portion 6 project laterally bracket portions 19 on the ends of which are formed tongues 20 to fit slits 21 in the fuselage portion, inside the slits 14, and on the rear edges of the 85 bracket portions 19 are formed leg portions 22 with feet.

To assemble the aeroplane from this blank the tail portion 7 and fuselage portion are folded upward along the longitudinal lines 90 8 and 11 as previously described.

The wing portion 5 is then folded rearwardly over the fuselage portion, on the transverse lines 23, 24, and 25, and the bracket portions 19 are folded upward on 95 the longitudinal lines 26 connecting them with the fuselage 6.

The side edges of the fuselage portion 6 correspond and are brought into coincidence with and rest against the now upwardly pro- 100

jecting edges of the fuselage portion from the points 12 to the rear ends of the lines 16, forming the box-like bow of the aeroplane, and the forward edge of the wing portion 5 is inserted in the slits 14, of the fuselage portion, the opposite sides of which are at the same time inserted in the slit 18 in the wing portion. The wing of the aeroplane is thus shaped by the curved edges 15 and held in place, while the sides of the fuselage are formed and held in place all as shown in Figures 2, 3, and 4.

The tongues 20 of the bracket portions 19 are then inserted in the vertical slits 21 and the legs formed by the leg portions 22, fixed in position below the box-like bows of the aeroplane to uphold the aeroplane in conjunction with the tail as shown.

It is evident that many changes may be made in the specific embodiment of my invention without departing from its boundaries as defined by the following claims.

I claim as my invention:

1. A flexible blank for forming a toy aeroplane, of roughly T-form, having a wing portion, a tail portion adapted to be folded upward on a medial longitudinal line, and a fuselage portion between the wing and tail portions formed with oppositely extending bracket portions having rearwardly extending leg portions, and end tongues, the blank being formed with slits to receive the wing portion when said wing portion is folded backward, and with slits to receive the tongues on the bracket portions.

2. A toy aeroplane blank or sheet of rough T-form comprising a tail portion foldable upward on a medial longitudinal line extending forward between two diverging lines, and having edge slits and inside slits on both sides of said tail, a fuselage portion forming a part of said tail portion, a wing forming a part of said fuselage portion, said wing portion being foldable backward over the fuselage portion and insertable in the edge slits in said tail, bracket portions extending oppositely from the fuselage portion, tongues and legs forming a part of said bracket portions, said bracket portions carrying the tongues and legs being foldable backwardly from the sides of the fuselage and the tongues insertable in the inside slits to fix the legs in supporting position.

3. A toy aeroplane blank comprising a sheet of rough T-form comprising a tail portion foldable upward on a medial longitudinal line, a fuselage portion forming a part of said tail portion, a wing portion forming a part of said fuselage portion, said wing portion being foldable backwardly over the fuselage portion, means on said fuselage portion and said wing portion for securing the said wing portion in folded position, bracket portions extending oppositely from the fuselage portion, means on said bracket portion

and said fuselage for locking said brackets in supporting position.

4. A toy aeroplane blank comprising a sheet of rough T-form comprising a tail portion foldable upward on a medial longitudinal line and having edge slits and inside slits on both sides of said tail, a fuselage portion forming a part of said tail portion, a wing portion forming a part of said fuselage portion, said wing portion being foldable angularly backward over the fuselage portion and insertable in the edge slits in the said tail, bracket portions extending oppositely from the fuselage portion, tongues and legs forming a part of said bracket portion, the said bracket portions carrying the tongues and legs being foldable backwardly from the sides of the fuselage.

5. A toy aeroplane forming a blank or sheet of rough T-form comprising a tail portion foldable upward on a medial longitudinal line extending forward between two diverging lines, a fuselage portion forming a part of said tail portion, a wing formed by a part of said fuselage portion, said wing portion being foldable backward over the fuselage portion, means carried by said wing portion and tail portion adapted to secure said wing portion in folded position, means extending from said fuselage portion and forming a part thereof for supporting said fuselage.

In testimony whereof I affix my signature.

JOSEPH EDWIN BURGESS.
